CLAIM

The ornamental design for a razor blade scraper holder or similar article, as shown and described.

DESCRIPTION

FIG. 1 is a top plan view of a razor blade scraper holder or similar article showing my new design;

FIG. 2 is an end elevational view as seen from the left of FIG. 1;

FIG. 3 is a sectional view, through section lines 3—3 of FIG. 1, showing details of a pivot button;

FIG. 4 is a bottom plan view thereof;

FIG. 5 is an end elevational view as seen from the right of FIG. 1;

FIG. 6 is a reduced top perspective view thereof; and

FIG. 7 is a slightly reduced bottom perspective view of FIG. 1.

FIG. 1

FIG. 3

FIG. 4

FIG. 2

FIG. 5
